UNITED STATES PATENT OFFICE

THOMAS WILLIAM MERTZ, OF WEBSTER SPRINGS, WEST VIRGINIA

FUSE PLUG

Application filed December 13, 1930. Serial No. 502,198.

This invention relates to safety fuse plugs for preventing the accidental, careless, or deliberate over-fusing of a circuit, of new and novel design and composition whereby features of novelty and advantage not heretofore achieved are accomplished in a fuse plug of simple and inexpensive, and attractive design.

It is an object of this invention to provide a fuse plug of the type referred to, which automatically prevents the over-fusing of the same with the consequent damage to the circuit, though it may be underfused, by providing certain features of novelty and construction which will be set out below.

It is also an object of this invention to provide a fuse plug of the type described, which cannot easily be removed, since it is provided to be locked in place.

It is also an object of this invention to provide a fuse plug of the type described, which cannot be bridged, and hence is safe in operation and protected from premeditated or accidental tampering.

It is also an object of this invention to provide a fuse plug of the type described, which may be made of a variety of materials like bakelite, hard rubber, porcelain or glass, or of any suitable material, and of any color and which may be made in the form of a screw plug for association with the ordinary type of fuse block or board, and which might if desired, be made a part of the panel board to replace the fuse socket, thus eliminating the use of the fuse sockets with resultant increased safety and convenience.

It is also an object of this invention to provide a fuse plug of the type described, which may be re-fused without removing the same from its association in a circuit.

These and other objects of the invention, its nature, and composition and arrangement and combination of parts will be readily understood by any one acquainted with the art to which this invention relates upon consulting the following descriptions of the drawings wherein:—

Figure 1 is a general side elevational view of my improved fuse plug.

Fig. 2 is an end view thereof, taken from the right of Fig. 1 and

Fig. 3 is a longitudinal vertical cross sectional view taken on the line 3—3 of Fig. 2.

Fig. 4 is a transverse vertical cross sectional view approximately on the line 4—4 of Fig. 3, and

Fig. 5 is a similar vertical transverse cross sectional view approximately on the line 5—5 of Fig. 3.

Fig. 6 is a longitudinal vertical and approximately central sectional view like that of Fig. 3, but Fig. 6 shows the core withdrawn outwardly of the shell of the plug.

Fig. 7 shows an elevational view similar to Fig. 1, with the exception that Fig. 7 shows the core withdrawn from the shell and the slots in the core and in the shell in alined position.

Fig. 8 is an elevational view of the core itself in the position in which it is found in Fig. 1.

Fig. 9 is a similar view to Fig. 8, taken at right angles thereto, on the longitudinal axis of the core.

Referring in detail to the drawings, the numeral 5 designates generally the shell of the fuse plug which may have the screw threaded portion 6 and associated central contact thereon 7. The numeral 8 designates generally the core of my fuse plug which is adapted to have a portion projected into, that is, telescoped into the shell 5. The core is provided with a handle portion 9 something in the form of a door knob. The shell 5 consists of a hollow cylindrical body having one end closed and the other opened to receive the said core slidably or telescopically therein.

As seen in Fig. 4 an intermediate portion of the shell 5 is transversely cut to a distance half way through as indicated at 10. The width of this cut or slot 10 is such as to exclude from positioning therein a larger size fuse wire than the stated capacity of the particular plug. Referring to Fig. 3, it will be observed that the numerals 11 and 12 refer to a pair of diametrically opposed contacts which are connected by means of wires 13 and 14 led to the contact 7 and to the screw threaded exterior portion 6 of the shell 5.

At 90° from the terminals of the slot 10, the shell 5 carries a pin or dowel 15 projecting inwardly to engage certain portions of the core to be described. As observed in Fig. 1, the pin 15 is disposed near the outer end of the shell 5.

As before stated, the core 8 though snugly fitted, slides or telescopes within the shell 5, but the withdrawal movement of the core 8 is limited by the pin 15 which engages in a slot 16 formed from a point within the outer end of the core to an intermediate portion thereof where it communicates with the peripheral groove 17.

15 It will be understood that when the pin 15 is engaged in the slot 16, the core may be withdrawn from the shell until the pin 15 abuts the rear wall of the peripheral slot 17 but no farther. It will also be understood 20 that the core may not be rotated except when the pin 15 is disposed in the peripheral slot 17. The reason for the provision of the structure just described will be better understood as the description proceeds further.

25 It will be observed in the drawings that the inward end of the core 8 is formed with slight taper 18. It will also be observed that diametrically disposed at 90° from the slots 16 there is provided near the inward end of the 30 core a relatively large cylindrical bore 19 formed completely through the core.

A slot 20 at right angles to the bore 19 communicates with said cylindrical bore as particularly well seen in Fig. 9.

35 As already stated contacts 11 and 12 are exposed at diametrically opposite points in the interior wall of the shell 5. Somewhat outward of the contacts 11 and 12, there are provided other and similarly diametrically 40 oppositely placed metal pieces 21, 22 immediately adjacent the cut or slot 10 as particularly well seen in Fig. 4. Through the core 8 is a small longitudinal bore 23 in which is loosely slidable a rod 24 having a disk or the like 25 disposed on its inward end which is arranged in a depression or recess 26 in the wall of the cylindrical bore 19.

The outer end of the bar 24 has a handle 27. At 90° from the terminals of the slot or cut 50 10 in the shell there is provided a longitudinal slot 28 which extends from an intermediate portion of the shell to the end thereof.

With the arrangement described above, it will be obvious that by withdrawing the core 55 the required distance it may be rotated to bring its enlarged cylindrical bore 19 into registry with the enlarged slot 28 in the shell as shown in Fig. 7. In this position, it is obvious that any fuse wire or strip which may 60 lie in a U-shaped form over the tapered end of the core as shown in Fig. 3, may be easily removed.

To refuse the plug, the core is withdrawn to the limit from the shell and the proper 65 fuse wire or the like passed through the slot

10 so that it extends on a diameter of the shell. It is part of my invention to provide a fuse plug of the type described which is adapted to cut its own fuse wire, and, therefore, the metallic pieces 21 and 22 are provided to shear a length of the proper dimension upon the forcing of the core inwardly against said wire strip, in which action the shoulder 31 cooperates with the shearing blocks 21 and 22 to cut the fuse link.

70 As shown in Fig. 3, the continued inward movement of the core 8 carries the fuse strip wire 29, once it has been sheared, and deforms it from the position shown in Fig. 6. It will be seen that the fuse wire in Fig. 3 has 75 conformed itself to the tapered portion of the tapered slots 30 leading from the outward wall of the cylindrical bore 19, in which position the limit of the motion of the bore inward will place the ends of the fuse wire 80 or strip firmly in contact with the contacts 11 and 12. The portions between the ends of the slots 30 and the peripheral groove 17 form the shearing blocks 31 for cooperation 85 with the elements 11 and 12.

90 It will be observed that should the wire or strip attempted to be used in re-fusing the plug be too hard or be of material of a greater tenacity than the proper kind of fuse wire or strip, the same would not be cut 95 readily by the shearing action of the plug and shell and the inferior or improper character of the fusing material attempted to be inserted would be immediately evidenced, by the refusal to shear or to properly conform itself, or producing a jam.

100 When the strip or wire is in proper position and not blown out, the rod 24 will indicate this condition by its refusal to be freely projected into the cylindrical bore 19. 105 Whereas, should the fuse material be blown out, the rod 24 may be freely pushed in up to its limit, and this will invariably indicate the condition of the fuse material, without necessitating the taking apart of the fuse 110 plug.

115 The method of discharging the blown fuse material has already been described and shown in the drawings, particularly in Fig. 7, and the simplicity of the removing operation will now be clearly seen. An additional feature of interest is the provision of the taper or wedge screws 32 which are adapted to expand the ferrule 6 against the interior of the socket receptor whereby the plug assembly is locked securely to the panel, mounting board or the like.

120 It will now be recognized that I have provided a very efficient and desirable fuse plug of the type described presenting features of novelty and advantage resulting in convenience and safety factors not heretofore achieved in a device of the character described. The extreme and admirable usefulness and convenience of my invention cannot 125

be over-estimated, since it saves time, is more efficient than existing devices, is safe to use and operate, protects against over-fusing and damaged circuits, and provides for entirely doing away with the screw plug type of fuse plug and has other advantages and features of novelty as set out herein.

It is to be definitely understood that I do not desire to limit the application of this invention to the particular modifications set out herein, to illustrate the principles thereof, and any change or changes may be made in structure and arrangement of parts as well as in materials, within the spirit and scope of the invention.

Having thus described my invention, what I claim as new is:—

1. A safety fuse plug of the type described comprising a tubular shell having a longitudinal slot and a core provided with a transverse bore and adapted to telescope into said shell, a pin on the shell, said core having grooves adapted to be engaged by the pin for limiting the withdrawing thereof from the shell but permitting relative rotation, a piece of fuse wire, said bore in the core being registrable with said longitudinal slot to permit withdrawing and replacing the fuse wire from the interior of the shell, said shell having a transverse slit through which said fuse wire is to be passed to the interior of the shell for limiting the size of fuse wire to be used in the plug.

2. A safety fuse plug of the type described comprising a tubular shell having one end closed and provided with a screw threaded socket engaging ferrule, and an end contact and having its end open, a pair of contacts in the shell connected to said ferrule and end contact, a core adapted to be telescoped into said shell, a piece of fuse wire, said core having a transverse bore adapted to receive a length of the fuse wire, said shell having a transverse measuring slit for limiting the size of fuse wire to be secured in said bore, a length of fuse wire, placed in said bore and being adapted to be sheared between the sides of the bore and one edge of said slit so as to cut the fuse wire to the proper length upon inward movement of the core, said core adapted to move further inwardly after shearing the fuse wire to bend the end portions of the cut length of fuse wire and wedge the ends thereof between the core and the pair of contacts in the shell.

3. A safety fuse plug of the type described comprising a tubular shell having one end closed and provided with a screw threaded socket engaging ferrule and an end contact, a pair of contacts in the shell and connected to said ferrule and end contact and having its other end open, a core adapted to telescope into said shell, a piece of fuse wire, said core having a transverse bore, adapted to receive said fuse wire, said shell having

a transverse measuring slit through which said fuse wire must pass into said bore, said fuse wire being adapted to be sheared between the sides of the core and one edge of said slit, so as to cut the fuse wire to the required length upon inward movement of the core, said core being adapted to move further inwardly after having sheared the fuse wire so as to bend the end portions of the cut length of fuse wire and wedge the ends thereof between the core and the pair of contacts in the shell, and a fuse wire tester rod longitudinally movable in said core for contacting the intermediate portion of a length of fuse wire so positioned.

4. A safety fuse plug of the type described comprising a tubular shell having one end closed and provided with a screw threaded socket engaging ferrule and an end contact, and having its other end open, a core, adapted to telescope into said shell, a piece of fuse wire, said core having a transverse bore, adapted to receive said fuse wire, said shell having a transverse measuring slit through which said fuse wire is to be passed into said bore, said fuse wire being adapted to be sheared between the sides of the core and one edge of said measuring slit so as to cut the fuse wire to the required length upon inwardly moving the core, said core being adapted to be further moved inwardly, to bend the end portions of the cut length of fuse wire and wedge them between the core and the pair of contacts in the shell, a fuse wire tester rod longitudinally movable in said core for contacting the intermediate portion of a length of fuse wire so positioned, said shell being provided with a longitudinal slot opposite said measuring slit registrable with said transverse bore in the core to permit the removal of so positioned fuse wire.

5. A safety fuse plug of the type described comprising a tubular shell having one end closed and provided with a screw threaded socket engaging ferrule and an end contact and having its other end open, a core adapted to telescope into said shell, a piece of fuse wire, said core having a transverse bore adapted to receive said fuse wire, said shell having a transverse measuring slit through which said fuse wire is to be passed into said bore, said fuse wire being then adapted to be sheared between the sides of the core and the one edge of said slit so as to cut the fuse wire to the required length upon inwardly moving the core, said core being adapted to be moved further inwardly so as to bend the end portions of the cut length of fuse wire and wedge them between the core and the pair of contacts in the shell, a fuse wire tester rod longitudinally movable in said core for contacting the intermediate portion of the so positioned fuse wire, said shell being provided with a longitudinal slot opposite said measuring slit registrable with said

- transverse bore in the core to permit the removal of said so positioned fuse wire, said core being formed with a transverse peripheral groove, and a longitudinal groove running from a point within the outward end of the core into said peripheral groove, a pin projected from the wall of the shell for engagement in said peripheral and longitudinal grooves for permitting relative rotation of the shell and core while limiting complete withdrawal of the core from the shell.
6. A safety fuse plug of the type described comprising a tubular shell having one end closed and provided with a screw threaded socket engaging ferrule and an end contact and having its other end open, a core adapted to be telescoped into said shell, a piece of fuse wire, said shell having a transverse bore, adapted to receive said fuse wire, said shell having a transverse measuring slit through which said fuse wire is to be passed into said bore, said fuse wire being adapted to be sheared between the sides of the core and one edge of said slit so as to cut the fuse wire to the proper length upon inwardly moving the core, said core being adapted to be moved further inwardly so as to bend the end portions of the cut length of fuse wire and wedge the ends thereof between the core and the pair of contacts, a fuse wire tester rod longitudinally movable in said core for contacting the intermediate portion of the fuse wire thus positioned, said shell being provided with a longitudinal slot opposite said measuring slit and registerable with said transverse bore in the core to permit the removal of the said thus positioned fuse wire, said core being formed with a transverse peripheral groove and a longitudinal groove running from a point within the outward end of the core into said peripheral groove, a pin projected from the wall of the shell for engagement in said peripheral and longitudinal grooves for permitting relative rotation of the shell and core while limiting complete withdrawal of the core from the shell, and a handle on the outward end of the core.
7. A safety fuse plug of the type described comprising a tubular shell having one end closed and provided with a screw threaded socket engaging ferrule, and an end contact and having its other end open, a core adapted to be telescoped into said shell, a piece of fuse wire, said core having a transverse bore, adapted to receive said fuse wire, said shell having a transverse measuring slit through which said fuse wire is to be passed with said bore, said fuse wire adapted to be sheared between the sides of the core and one edge of said slit for cutting the fuse wire to the required length upon inwardly moving the core, said core being adapted to be moved further inwardly to bend the end portions of the cut length of fuse wire and wedge the ends between the core and the pair of contacts in the shell, a fuse wire tester rod longitudinally movable in said core for contacting the intermediate portion of the fuse wire thus positioned, said shell being provided with a longitudinal slot opposite said measuring slit and registerable with said transverse bore in the core to permit the removal of said positioned fuse wire, said core being formed with a transverse peripheral groove and a longitudinal groove running from a point within the outward end of the core, into said peripheral groove, a pin projected from the wall of the shell for engagement in said peripheral and longitudinal grooves for permitting relative rotation of the core from the shell, a handle on the outward end of the core, a metallic cutting bar at the said one edge of said transverse measuring slit in said shell adapted to cooperate with one edge of the peripheral groove in the core to cut fuse wire of the proper softness only.
- In testimony whereof I affix my signature.
